MOP WRINGING APPARATUS

Edward Pavek, Minneapolis, Minn.

Application February 23, 1933, Serial No. 657,956

20 Claims. (Cl. 15—261)

This invention relates to a mop wringing apparatus, and while the apparatus is capable of being secured to a pail and mounted on the pail in various manners, it particularly is illustrated as a device having means supporting it upon the edge of the pail and being readily removable from the pail.

It is an object of this invention to provide a mop wringing apparatus comprising plates relatively swingable toward and from each other to squeeze a mop therebetween, means for swinging one of said plates and means simultaneously engaging the other plate to move it with increasing leverage as said plates approach each other.

It is a further object of the invention to provide a mop wringing apparatus comprising a pair of plates relatively swingable about a pivot toward and from each other to squeeze a mop therebetween, means for swinging one of said plates, means simultaneously engaging the other plate to move it toward said first mentioned plate, said last mentioned means being movable toward the axis of said pivot as said plates approach each other.

It is a further object of the invention to provide a mop wringing apparatus comprising a frame, a plate pivoted in said frame, a second plate connected to said first mentioned plate, a roller carried by said second plate and a cam engaged by said roller as said first mentioned plate is swung to move said second plate toward said first mentioned plate, together with a guide means for said roller.

These and other objects and advantages of the invention will be fully set forth in the following description made in connection with the accompanying drawings, in which like reference characters refer to similar parts throughout the several views and in which:

Fig. 1 is a view in vertical section of the apparatus supported by a pail, taken on line 1—1 of Fig. 2, as indicated by the arrows;

Fig. 2 is a view in end elevation of the device, the supporting pail being shown in vertical section;

Fig. 3 is a top plan view of the device;

Fig. 4 is a partial view of the upper portion of Fig. 1, shown on an enlarged scale;

Fig. 5 is a substantially horizontal section taken on line 5—5 of Fig. 4, as indicated by the arrows;

Fig. 6 is a view similar to Fig. 1, showing the parts in mop-squeezing position;

Fig. 7 is a horizontal section taken on line 7—7 of Fig. 1;

Fig. 8 is a view in side elevation of a modified form of the mop stick engaging means;

Fig. 9 is a top plan view of Fig. 8; and

Fig. 10 is a view in side elevation of Fig. 8, as seen from the left thereof, Figs. 8, 9 and 10 being shown on an enlarged scale.

Referring to the drawings, particularly Figs. 1 to 7, a pail 20 is shown adapted to contain wash water such as usually used in mopping floors. A frame member 21 is shown, and while this frame member might be secured to or supported in the pail in various ways, in the embodiment of the invention illustrated it is shown as having a pair of side plates 21a, each of which has a slot portion 21b at one side forming a tongue or hook 21c adapted to extend over the edge of the side or partition 20a of the pail 20. The said side or partition extends into the slot 21b and the side portions 21a have their edges extending downwardly along the side or partition 20a and said side portions extend substantially at right angles to said side or partition. The side plates 21a are connected by headed rivets 22 having their heads at the outer sides of the side plates, which rivets have thereon and extend through sleeves or tubular members 24 engaging the adjacent sides of said side plates. A pivot member 25 extends through side plates 21a, having washers 26 at the outer sides of said plates held in place by pins or split key members 27 extending through pivot 25 at the outer side of the washers 26. It may be stated that side plates 21a are connected at their lower ends by a portion 21d extending therebetween adjacent the bottom of pail 20. The pivot 25 extends through arcuate slots 28a formed in the parallel side portions 28b of a plate 28. Plate 28 as clearly shown in Figs. 1 and 3 extends substantially the distance between the side plates 21a and plates 28b extend in parallel relation and parallel to the side plates 21a. The side portions 28b have a plurality of holes 28d therethrough. Plate 28 is slightly curved at its bottom and formed with hinged lugs through which extends a hinged pintle 29 also extending through hinged lugs at the bottom of the plate 30 interfitting with the lugs on plate 28 so that plates 28 and 30 are hinged together at their bottom portions. Plate 30 extends between the side portions 28b and above the same, said plate having a portion 30a bent outwardly and downwardly at its upper end. Portion 30a has a slot 30b formed therein through which extends a member or bar 31 connected at its lower portion to the rear of plate 30 by some suitable fastening means such as the rivets 32. Member 31 has an upper portion 31a extending

forwardly of plate 30 substantially at right angles, and side portion 31a is bent into U shape so as to have parallel side portions. Said parallel side portions are each provided with a slot 31b and a stud 33 extends through said slots, being threaded at each end to receive nuts 34 which engage the washers 35 disposed at the outer sides of portion 31a and extending across the slots 31b. Stud 33 has a sleeve 36 thereon extending between the sides of portion 31a and on which is journaled a roller 37 having a concave groove in its periphery. It will be seen that the stud 33 can be disposed in different portions in the slots 31b, the same being movable when nuts 34 are loosened and being capable of being tightened in the desired position by said nuts. The plate 28 at its outer side or the side remote from plate 30 has a pair of bearing sleeves 38 secured thereto in any suitable manner, as by welding, and a rod 39 extends through and between said sleeves, being journaled therein and having at its ends rollers 40 secured thereto. The rollers 40 rest upon and are adapted to travel along a cam surface 28c formed on the top of each side plate 21a as shown in Fig. 1. Curved guide rods 41 are secured in the plates 21a at the outer end of the cam track 28d and extend in curved formation some distance over said cam tracks.

In operation, when a mop is to be squeezed, the same will be disposed between the plates 28 and 30 as they are in the position shown in Fig. 1. The operator then disposes the mop stick 42 in the position shown in dotted lines in Fig. 1, the same being disposed between the sides of portion 31a and in contact with the roller 37. The operator can now swing the handle to the left as shown in Fig. 1 and this causes plate 30 to swing about the axis of pintle 29 and move toward plate 28. As plate 30 is thus swung, the lower end thereof moves to the right and due to the resistance of plate 28 and the presence of the mop between said plates, pivot 25 moves to the left in slot 28a. The plates finally reach approximately the position shown in Fig. 6. It will be seen that the lower end of the plate 28 will be moved to the right in the lower end of plate 30 and the rollers 40 will be drawn along the cam track 28c. The axis of rollers 40 thus approaches the axis of the pivot 25 and an increasing leverage is had moving the plates together as bar 31 and mop handle 42 are swung to the left. The mop will thus be thoroughly squeezed and the water therefrom will run out between the bottoms of the side plates and through the holes 28d into pail 20. The operator can now swing the mop stick 42 to the right and thus move it parallel to plate 30 until it is out of line with portion 31a when the dry mop can be removed. It will be seen that if the mop is placed between the plates 28 and 30 in the position shown in Fig. 1, that the weight of the mop or any pressure exerted thereon will tend to move the plates together, as such weight or pressure tends to swing plate 28 downwardly. Members 41 form guides and stops for roller 40.

The mop can thus be quickly and easily squeezed without the necessity of the operator bending over the pail 20. It is more difficult to bend down over the pail and operate a lever or handle to squeeze the mop than it is to perform the operation above described and with the described operation the operator does not have to bring his face down over the pail 20 which usually contains hot water.

In Figs. 8 to 10 a bar 45 is shown, which will be used in place of the bar 31. The bar 45 has

a rivet 46 secured therein passing through an aperture in a hook member 47 having one portion extending parallel to one side of the bar 45 and having a protuberance 47a thereon engaging the side of the bar 45. A spring 48 surrounds rivet 46, bearing at one end against member 47 and at its other end against a washer 49 held in place by a screw 50 threaded into the rivet 46 and having a slotted head. Spring 48 is of coiled formation with a larger diameter 10 adjacent member 47 than adjacent the washer 49. Member 47 extends around the bar 45 and has a substantially semi-cylindrical hook portion 47b at its outer end.

In operation, when the mop is placed between plates 28 and 30, the operator will swing the mop handle 42 into the hook portion 47b of the plate 47 and bar 45 will be swung to the left as already described for bar 41. It will be noted that bar 47 can swing about the axis of rivet 20 46 as indicated by the dotted lines in Fig. 8 and can also swing toward and away from the plate 45 as indicated by the dotted lines in Fig. 9. The mop stick 42 can thus be moved in a somewhat irregular path and plate 47 will accommodate itself to such movement.

From the above description it is seen that applicant has provided a simple and yet very efficient structure of mop squeezing apparatus. The apparatus is adapted to be removably supported 30 in a pail as shown, or it may be permanently secured in a pail. The parts are comparatively few in number and can be strongly and ruggedly made. It is obvious that the device will have a high degree of utility for the purpose intended. 35

It will, of course, be understood that various changes may be made in the form, details, arrangement and proportions of the parts, without departing from the scope of applicant's invention, which generally stated, consists in a device 40 capable of carrying out the objects above set forth, in the parts and combinations of parts disclosed and defined in the appended claims.

What is claimed is:—

1. A mop wringer having in combination, a frame having means to engage over the edge of the pail and be supported thereon and having side portions, a plate pivotally mounted on said side portions and extending substantially the distance therebetween, a second plate swingingly connected to and facing said first mentioned plate, means for swinging said first mentioned plate relatively to said frame and toward said second mentioned plate, and means simultaneously engaging said second mentioned plate to move it with increasing leverage as said plates approach each other.

2. A mop wringer having in combination, a frame having means to engage over the edge of the pail and be supported thereon and having side portions, a plate swingingly mounted on a pivot carried in said frame, a second plate pivotally connected to and facing said first mentioned plate, said plates extending substantially the distance between said side portions, means 65 for swinging said first mentioned plate toward said second plate, and means for simultaneously engaging said second plate as said plates approach, said last mentioned means being movable toward and moving toward the axis of said 70 pivot as said plates approach each other.

3. A mop wringer having in combination, a frame having means to engage over the edge of the pail and be supported thereon and having side portions, a plate pivotally mounted on said 75

side portions and extending therebetween, a second plate swingingly connected to said plate adjacent the bottom thereof and facing said first mentioned plate, means for swinging said first mentioned plate relatively to said frame toward said second mentioned plate, and means for simultaneously engaging said second plate as said first mentioned plate moves, including a roller carried by said second plate and engaging said frame.

4. A mop wringer having in combination, a frame adapted to be supported on a pail and having side portions, a plate swingingly mounted on a pivot in said side portions and extending substantially the distance therebetween, a second plate swingingly connected to said plate adjacent the bottom thereof and at a point below said pivot and facing said first mentioned plate, said second plate having a roller secured thereto, said frame having a portion engaged by said roller, and means for swinging said first mentioned plate whereby said roller moves along said last mentioned portion and said second plate is moved with increasing leverage as said plates approach.

5. A mop wringer having in combination, a frame adapted to be supported upon a pail and having side portions, a plate swingingly mounted on a pivot carried in said side portions, a second plate swingingly connected to said plate and facing the same, means for swinging said first mentioned plate relatively to said frame and toward said second plate, and means simultaneously engaging said second plate as the same moves, said pivot being movable relatively to said frame in the movement of said first mentioned plate.

6. A mop wringer having in combination, a frame adapted to be supported in a pail and having side portions, a plate pivotally mounted on said side portions and extending substantially the distance therebetween, a second plate mounted in said frame and facing said first mentioned plate, a member extending upwardly from said first mentioned plate having means at its upper end adapted to be engaged by the stick of a mop to swing the same in said plate, said member being movable longitudinally of said plate.

7. A mop wringer having in combination, a frame adapted to be supported in a pail and having side portions, a plate pivotally mounted on said side portions and extending substantially the distance therebetween, a second plate mounted in said frame and facing said first mentioned plate, a member extending upwardly from said first mentioned plate, a member carried at the upper end of said last mentioned member adapted to be engaged by the stick of a mop, which stick extends along said first mentioned plate, said first mentioned member being movable longitudinally of said plate, and resilient means holding said first mentioned member in normal position.

8. A mop wringer having in combination, a frame adapted to be supported in a pail and having a side portion, a plate pivoted in said frame, a second plate connected to said first mentioned plate and facing the same, said side portion having a cam surface thereon, a roller carried by said second plate adapted to engage said cam surface, and means for swinging said first mentioned plate and causing movement of said second plate relatively to move said plates toward each other, said cam roller approaching the pivot about which said first mentioned plate swings, as said plates approach each other.

9. A mop wringer having in combination, a frame adapted to be supported in a pail and hav-

ing a side portion, a plate pivoted in said frame, a second plate connected to said first mentioned plate and facing the same, said side portion having a cam surface thereon, a roller carried by said second plate adapted to engage said cam surface, means for swinging said first mentioned plate toward said second plate and moving said second plate to cause said roller to move along said cam surface, said cam surface having a depression therein at one end in which said roller is disposed when said plates are in separated position.

10. A mop wringer having in combination, a frame adapted to be supported in a pail, said frame comprising spaced side plates, said side plates having arcuate slots therein, a pivot extending through said slots, a plate connected to said pivot to swing about the axis thereof, a second plate in said frame facing said first mentioned plate and connected thereto below said pivot, means for swinging said first mentioned plate toward said second plate, said pivot moving in said slots as said plates approach each other.

11. A mop wringer having in combination, a frame adapted to be supported in a pail, a pair of oppositely disposed plates in said frame adapted to receive a mop therebetween, said plates being pivotally connected at their lower ends and diverging upwardly from their lower ends one of said plates being swingable toward the other, a member extending upwardly from said plate having means at its upper end adapted to be engaged by the stick of a mop to be squeezed for swinging said plate, and means engaging the other plate to cause approaching movement of said plates with increasing leverage as one plate approaches the other.

12. A mop wringer having in combination, a frame adapted to be supported in a pail and having spaced side portions, said portions having cam tracks formed thereon, a plate mounted on a pivot extending transversely of said side plates, a second plate pivotally connected to said first mentioned plate, rollers carried by said second plate adapted to respectively engage said cam portions, and means engageable by a mop stick for swinging said first mentioned plate and simultaneously causing movement of said second plate, said rollers moving along said cam tracks and approaching the axis of said pivot as said plates approach each other.

13. A mop wringer having in combination, a frame adapted to be supported in a pail, a plate mounted for swinging movement in said frame, a second plate pivotally connected to and facing said first mentioned plate, said plates being relatively movable toward and from each other so that a mop can be squeezed therebetween, and means for swinging said first mentioned plate to cause approaching movement of said plates, said second plate being moved by said movement of said first mentioned plate through its pivotal connection therewith, said plates moving bodily with respect to said frame in said approaching movement and stationary means engaged by said second plate for controlling its movement.

14. A mop wringer having in combination, a frame, a plate pivotally mounted in said frame for swinging movement relatively thereto, a second plate facing said first mentioned plate, a member extending upwardly from said first mentioned plate, a member carried at the upper end of said last mentioned member adapted to be engaged by the stick of a mop and being movable relatively to said last mentioned member and re-

- silient means holding the same in normal position.
15. A mop wringer having in combination, a frame, a plate pivotally mounted in said frame for swinging movement relatively thereto, a second plate pivotally connected to said first mentioned plate, means for swinging said first mentioned plate toward said second plate, a member carried by said second plate at the side thereof opposite said first mentioned plate and a member engaged by said last mentioned member for resisting movement of said second plate away from said first mentioned plate and assisting in causing approaching movement of said plates.
15. 16. A mop wringer having in combination, a frame, a plate pivoted in said frame, a second plate connected to and facing said first mentioned plate, a roller carried by said second plate, a cam surface engaged by said roller and on which said roller moves, means for swinging said first mentioned plate and causing movement of said second plate and roller, and guide means for said roller as it moves on said cam surface.
17. A mop wringer having in combination, a frame, a plate pivotally mounted in said frame for swinging movement relatively thereto, a second plate connected to said first mentioned plate and facing the same, a roller carried by said second plate at the side thereof opposite said first mentioned plate, a cam track engaged by said roller, means for swinging said first mentioned plate and causing movement of said second plate and roller for causing said plates to approach each other and a stop member for limiting the movement of
- said roller when said plates are in separated position.
18. A mop wringer having in combination, a frame adapted to be supported in a pail, a pair of plates hingedly connected by a pivot member for swinging movement toward and from each other about said pivot, means moving in said frame for guiding one plate in its movement, means engaging the outer side of the other plate to control its movement and means rigid with one of said plates for swinging said plates together and apart.
19. A mop wringer having in combination, a frame adapted to be supported in a pail, a pair of plates hingedly connected by a pivot member for swinging movement toward and from each other about said pivot, means movable with one of said plates for guiding it relatively to said frame, means engaging the outer side of the other plate to control its movement, said pivot being movable with said plates and relatively to said frame in the swinging movement of said plates.
20. A mop wringer having in combination, a frame, a pair of plates mounted therein for relative swinging movement toward and from each other, a pivot member connecting said plates for relative swinging movement, a guide member secured to one of said plates, said frame having a guide means in which said member moves in the swinging movement of said plates and means for relatively swinging said plates, moving said guide member and also moving said pivot member.

EDWARD PAVEK.
